UNITED STATES PATENT OFFICE.

JOHN ERNEST MINNITT AND JOHN HENRY VICKERS, OF NOTTINGHAM,
ENGLAND.

APPARATUS FOR AUTOMATICALLY CLOSING THE TAP-HOLES OF CASKS.

SPECIFICATION forming part of Letters Patent No. 334,970, dated January 26, 1886.

Application filed September 8, 1885. Serial No. 176,482. (No model.) Patented in England November 5, 1884, No. 14,634.

To all whom it may concern:

Be it known that we, JOHN ERNEST MINNITT, lace-manufacturer, and JOHN HENRY VICKERS, contractor, both subjects of the Queen of England, residing at Nottingham, England, have invented new and useful Improvements in Apparatus for Automatically Closing the Tap-Holes of Beer and other Casks or Vessels, rendering corks unnecessary, parts of the apparatus facilitating the operation of tapping, (for which we have made application for British Letters Patent, dated November 5, 1884, No. 14,634,) of which the following is a specification.

Our said invention has for its object the construction or arrangement of apparatus for fitting inside a beer or other cask or vessel, for the purpose of automatically closing the tap-hole of a barrel on the withdrawal of a tap, thus rendering the insertion of a cork in the hole unnecessary, and by stopping the admission of air to the interior of the cask preventing fouling or other detrimental action in the cask or vessel. Part of the apparatus also facilitates the operation of tapping, rendering such operation less inconvenient and unpleasant by preventing the issue of the fluid in the vessel when inserting the tap.

Our invention consists in certain improvements in the construction of apparatus for closing the tap-holes of barrels or casks and in the combination of its several parts, substantially as hereinafter fully described, and as specifically pointed out in the claim.

The metal parts of the apparatus may be formed of any suitable metal, but are preferably formed of cast-iron, with the exception of the spring, which is of steel, and the metal parts are treated by any suitable well-known process whereby they are rendered not liable to corrosion and innocuous to the liquid contents of the cask to which they are fitted.

Figure 1 on the accompanying sheet of drawings is a horizontal section taken through the tap-hole of a cask fitted with our improved and simplified apparatus, and Fig. 2 is an end view looking from the inside of the cask.

The tap-hole 1 is fitted inside the cask 2 (part only of which is shown) with a flat rubber or caoutchouc ring, 3, which slightly over-

laps the tap-hole 1, and acts as a valve-seating. Over this rubber ring 3 there is placed a flanged end, 4, of a metal casting, 5, and both the ring 3 and casting 5 are secured to the cask-head round the tap-hole 1 by bolts 6. These bolts 6, of which there are preferably four, are passed through holes in the flanged end 4, rubber ring 3, cask-head, and, if preferred, through holes in a flat metal ring, 7, placed outside the cask round the tap-hole, and their heads are pressed against the flanged end 4 by means of nuts 8 screwed on the ends of the bolts, thus securing the whole firmly to the cask.

The flanged end 4 of the metal casting 5 is in the form of a flat ring, being of about the same diameter as the rubber ring 3, but of wider bore than the rubber ring and slightly wider than the tap-hole.

The metal casting 5, having the flanged end 4, consists of preferably four supports or guides, 9, arranged round the inner edge of the flanged end 4, so as to encircle a cylindrical space, and terminating at the inner end in a ring forming a flange, 10, projecting slightly inward. These guides 9 are preferably formed of triangular shape in cross-section, having their bases or broadest sides facing one another.

Inside the cylindrical space inclosed by the casting 5 there is fitted to slide freely a hollow metal cylindrical valve, 11, closed at the end or face nearest the rubber ring 3, and having cast on it a circular ridge, preferably V-shaped in cross-section, formed round its face near the edge. This ridge or circular projection is of greater diameter than the tap-hole, and is pressed against the rubber ring 3 and cask by the action of a helical spring, 12, which is inclosed within the casting 5 between the flange 10 at the inner end and a narrow flanged part on the inner end of the cylindrical valve 11, thus forming a self-closing valve. The helix of the spring 12 is of a size to fit freely inside the cylindrical space formed by the casting 5. When, however, a tap is inserted in the tap-hole 1 and forced upward, the tap end will press this cylindrical valve 11 back away from the rubber valve-seating and permit the contents of the cask to be withdrawn, while the overlapping rubber will have prevented the issue of any liquid during the tapping operation.

The foregoing arrangement and construction of the apparatus render it extremely simple and economical to manufacture, as the casting 5 and hollow cylindrical valve 11, being made of cast-iron, as described, render the fitting of the various parts together very simple, easy, and quick.

We claim as our invention—

The combination, substantially as herein described, with a cask, the valve 11, casting 5, and rubber gasket 3, of the face-ring 7, secured

outside of the cask around the tap-hole, and bolts passing through said face-ring and the flange 4 of the casting 5, said parts being constructed and arranged for co-operation substantially as and for the purpose specified.

JOHN ERNEST MINNITT.
JOHN HENRY VICKERS.
